US00RE48672E

(19) **United States**
 (12) **Reissued Patent**
 Peron

(10) **Patent Number:** US RE48,672 E
 (45) **Date of Reissued Patent:** Aug. 10, 2021

(54) **MEDICAL DRESSING**(71) Applicant: **Smith & Nephew PLC**, Watford (GB)(72) Inventor: **Yannick Louis Peron**, East Yorkshire (GB)(73) Assignee: **Smith & Nephew PLC**, Watford (GB)(21) Appl. No.: **29/709,413**(22) Filed: **Mar. 19, 2020****Related U.S. Patent Documents**

Reissue of:

(64) Patent No.: **Des. 679,820**Issued: **Apr. 9, 2013**Appl. No.: **29/389,783**Filed: **Apr. 15, 2011**

U.S. Applications:

(60) Continuation of application No. 29/639,290, filed on Mar. 5, 2018, now Pat. No. Re. 47,645, which is a continuation of application No. 29/548,270, filed on Dec. 11, 2015, now Pat. No. Re. 46,778, which is a division of application No. 29/510,717, filed on Dec. 2, 2014, now Pat. No. Re. 46,289, which is an application for the reissue of Pat. No. Des. 679,820.

(57) **CLAIM**

The ornamental design for a medical dressing, as shown and described.

DESCRIPTION

The present application is a continuation reissue application of U.S. Reissue application Ser. No. 29/639,290, which is a continuation reissue application of U.S. Reissue application Ser. No. 29/548,270, which is a divisional reissue application of U.S. Reissue application Ser. No. 29/510,717, filed Dec. 2, 2014, which is an application for reissue of U.S. Des. Pat. No. 679,820, filed Apr. 15, 2011, which claims priority to United Kingdom Design Registration No. 4017442, filed Oct. 15, 2010, and United Kingdom Design Registration No. 4017443, filed Oct. 15, 2010.

[FIG. 1 is a perspective top view of one embodiment of a medical dressing.]

[FIG. 2 is another perspective top view of the medical dressing of FIG. 1.]

[FIG. 3 is a top plan view of the medical dressing of FIG. 1.]

[FIG. 4 is a bottom view of the medical dressing of FIG. 1.]

[FIG. 5 is a far side view of the medical dressing of FIG. 1.]

[FIG. 6 is near side view of the medical dressing of FIG. 1.]

[FIG. 7 is a front view of the medical dressing of FIG. 1; and.]

[FIG. 8 is a rear view of the medical dressing of FIG. 1.]

FIG. 9 is a top, right-side, and front perspective view of a medical dressing.

FIG. 10 is a top, right-side, and rear perspective top view of the medical dressing of FIG. 9.

FIG. 11 is a top plan view of the medical dressing of FIG. 9.

FIG. 12 is a bottom plan view of the medical dressing of FIG. 9.

FIG. 13 is a left side elevation view of the medical dressing of FIG. 9.

FIG. 14 is a right side elevation view of the medical dressing of FIG. 9.

FIG. 15 is a front elevation view of the medical dressing of FIG. 9; and,

FIG. 16 is a rear elevation view of the medical dressing of FIG. 9.

The broken lines in the drawings illustrate portions of the medical dressing that form no part of the claimed design.

1 Claim, 16 Drawing Sheets

Matter enclosed in heavy brackets [ ] appears in the original patent but forms no part of this reissue; matter printed in italics indicates the additions made by reissue.
